UNITED STATES PATENT OFFICE.

JAMES HARRY KEIGHLY McCOLLUM, OF TORONTO, ONTARIO, CANADA, ASSIGNOR TO
GEORGE H. GOODERHAM, JOHN WYCLIFFE LOWES FORSTER, AND THE ARGYLLS
LIMITED, OF ALEXANDRIA, SCOTLAND.

INTERNAL-COMBUSTION ENGINE.

1,212,653.

Specification of Letters Patent. Patented Jan. 16, 1917.

Application filed May 29, 1909. Serial No. 499,216.

To all whom it may concern:

Be it known that I, JAMES HARRY KEIGHLY McCOLLUM, a subject of the King of Great Britain, and resident of the city of Toronto, county of York, Province of Ontario, in the Dominion of Canada, have invented certain new and useful Improvements in Internal-Combustion Engines, of which the following is a specification.

10 The invention relates to improvements in internal combustion engines, as described in the following specification and illustrated in the accompanying drawings that form part of the same.

15 The invention consists essentially in the novel construction and arrangement of parts whereby reciprocatory and lateral motions are imparted to a cylindrical valve to control the ingress and egress of the gases to and 20 from the cylinder.

The objects of the invention are, to facilitate the operation of internal combustion engines, to utilize the operating fluid to the fullest extent, and generally to provide an 25 engine of simple construction, smooth and even in its operation and particularly adaptable to motor cars and launches.

In the drawings, Figure 1 is a vertical 30 sectional view of the engine, showing the main shaft in cross section. Fig. 2 is a vertical sectional view of the engine on a plane through the main shaft. Fig. 3 is a plan view in section on the line *a*—*b* of Fig. 1. Fig. 4 is a cross sectional view on a plane 35 through the upper tier of valve ports. Fig. 5 is a diagrammatic view showing the relative positions of the ports of the valve and cylinder at the middle of the suction stroke of the piston. Fig. 6 is a diagrammatic 40 view showing the relative positions of the ports of the valve and cylinder at the middle of the compression stroke. Fig. 7 is a diagrammatic view showing the relative positions of the ports of the valve and cylinder at the middle of the power stroke. Fig. 45 8 is a diagrammatic view showing the relative positions of the ports of the valve and cylinder at the middle of the exhaust stroke.

Referring to the drawings, 1 and 2 are

casings forming respectively the main portion of the cylinder 3 and the water jacket 4, the casing 1 being slightly reduced in thickness at the upper end 5.

The upper end of the casing 2 is enlarged and extends upwardly beyond the casing 1 forming an annular recess 6.

7 and 8 are annular chambers formed in the enlarged upper end of the casing 2 separated by the wall 9.

10 and 11 are openings in the outer wall 60 of the upper portion of the casing 2 communicating with the chambers 7 and 8 respectively said openings being connected with the inlet and exhaust pipes 12 and 13 respectively.

14 are inlet ports arranged in a circumferential row in the inner wall of the annular chamber 7.

15 are the exhaust ports arranged in a circumferential row in the inner wall of the 70 chamber 8.

16 is a cap closing in the top of the casing 1 and fitted on to the reduced upper end 5 of the said casing and completing the cylinder or combustion chamber.

17 are inlet ports arranged in a circumferential row in the wall.

The cap 16 is formed with a double wall, the outer portion 19 thereof completing the water jacket 4 of the cylinder.

17 and 18 are the inlet and exhaust ports in the inner wall of the cap 16 arranged in radial alignment with the inlet and exhaust ports 14 and 15 respectively leading to the annular chambers 7 and 8 respectively.

22 is a lateral flange formed at the bottom end of the cap 16 and fitting into the annular recess 6.

23 is a cylindrical casing fitting within the enlarged upper portion of the casing 2 and abutting the outer portion of the flange 22 at the upper side and having the lateral flange 24 extending outwardly and over the top end of the casing 2.

25 are inlet ports through the casing 23 95 registering with the ports 14.

26 are exhaust ports in the casing 23 registering with the ports 15.

The casing 23 is secured to the upper end of the casing 2 by the bolts 27.

28 is a cylindrical valve having the inlet ports 29 arranged in a circumferential row 5 and adapted to register with the inlet ports 17 and 25.

30 are exhaust ports in the valve 28 adapted to register with the exhaust ports 18 and 26, said ports 30 being staggered in relation 10 to the ports 29.

The valve 28 fits snugly between the outer wall of the cap 16 and the inner wall of the cylindrical casing 23 and is adapted to reciprocate and rotate around said cap.

31 are packing rings arranged in suitable recesses in the outer wall of the cap 16, to each side of the inlet and exhaust ports and packing the valve 28.

32 is a spider secured to or forming part 20 with the valve 28 and having a stem 33 extending upwardly from the center thereof.

34 is a collar loosely surrounding the stem 33.

35 is a washer resting against the upper 25 side of the collar 34 and held in position by the nuts 36 threaded on said stem.

37 is a journal bracket extending inwardly from the inner wall of the casing 23.

38 is a short spindle or shaft journaled in 30 the bracket 37.

39 is a lever fixedly secured to the shaft 38 and extending outwardly through the slot 40 in the casing 23.

41 are arms fixedly secured to the ends of 35 the shaft 38 and extending inwardly from the center of the casing.

42 are pins extending through the inner ends of the arms 41 and secured in the collar 34, said pins being arranged diametrically 40 opposite one to the other and forming a pivot for the said arms.

The collar 34 fits loosely on the spindle 33 so as to allow a slight lateral movement of said collar on the tilting of the lever 34 and 45 arms 41, the said collar with said lever arms forming a means for reciprocating the valve 28.

43 is a bracket extending inwardly from the opposite side of the casing 23 to the 50 journal bracket 37. 44 is a shaft journaled in said bearing and extending outwardly from one end thereof and having a downward extension 45 at its outer end, said extension having a ball shaped end 46.

55 47 is an arm rigidly secured to the shaft 44 and extending outwardly through a slot 48 in the casing 23.

49 is a ball shaped stud fixedly secured to one of the radial arms of the spider 32 between 60 the center and the outer periphery of the valve.

50 is a connecting rod having the cup shaped end 51 embracing the ball end of the stud 49 and the cup shaped end 52 embracing 65 the ball shaped end 46 of the shaft 44.

53 and 54 are secondary crank shafts operatively connected with the main crank shaft 55 and journaled in suitable bearings.

56 is a connecting rod connecting the crank of the crank shaft 53 to the outwardly 70 extending end of the lever 39.

57 is a connecting rod connecting the crank of the shaft 54 to the arm 47, secured to the shaft 44. An operating connection is thus established between the shafts 38 75 and 44 with the main shaft and the valve 28 is operated to open and close the ports leading to the cylinder, as more particularly set forth hereinafter.

58 is a cap covering in the upper end of 80 the casing 23 and secured to the flange 24 by the bolts 27, said cap having a central opening 59 therethrough to receive the end of the stem 33.

60 is an inlet opening in the side wall of 85 the casing 2 leading to the water jacket 4 and communicating with the water supply the circulation of water being directed upward through the water jacket and the cap 16 by a partition wall 61 arranged immediately below the opening 60 and extending upwardly to a point adjacent to the top of the cap 16, as shown in dotted lines in Fig. 2.

62 are tubular casings extending downwardly from the cup 58 and communicating with the combustion chamber and having the spark plugs 63 secured therein, said tubes extending between the arms in the spider 32 and forming protecting casings 100 for the electric wires leading to said plugs.

In the operation of this device the secondary crank shafts 53 and 54 are suitably driven from the main shaft 55 of the engine and as the piston operates within the cylinder, said secondary shafts are rotated and through the connections hereinbefore described operate the cylindrical valve 28, the rocker formed by the lever 39 and arms 41 reciprocating the said valve and the arm 47 110 and connecting rod rotating said valve. When the valve 28 is in the position just beginning to open the inlet ports, the crank of the secondary shaft 54 is in substantially right angular relation to the connecting rod 115 connecting said crank with the arm 47 and as the said crank rotates the shaft 44 is rocked in its bearings and through the connecting rod 50 rotates the valve 28 opening the said inlet ports. As the crank of the shaft 54 is substantially at right angles to the connecting rod at the beginning of the opening of the inlet ports, the said valve is rotated to open the said ports very quickly and as the said secondary shaft 54 continues 120 its rotation the connecting rod 57 to said crank is retarded in its vertical movement through the crank approaching the dead center, consequently the motion of the valve is retarded and the ports held opened. Co- 125

incident with the retarding of the rotary movement of the valve 28, the crank of shaft 53 approaches the position of right angular relation with the connecting rod 56 connecting said crank to the rocker arm 39 and consequently the movement imparted to said rocker arm will increase in rapidity, reaching the fastest point of its movement when said crank and connecting rod are in right angular relation. The rocker arm then lifts upwardly on the valve 28 so that both the inlet and exhaust ports in said valve are moved above the inlet and exhaust ports respectively in the cylinder head and above the packing rings in the outer portion of the cap 23. A very quick closing of the inlet ports is thus obtained and the said ports are completely closed just prior to the upward movement of the piston in its compression stroke. As the inlet and exhaust ports in the valve 28 are arranged the same distance apart vertically, as the ports in the cylinder head, both the inlet and exhaust ports in said valve are raised by the movement of said rocker arm above and clear of the ports in said cylinder and packed securely by the packing rings in the cap 23. During the compression and expansion stroke of the piston the secondary shafts 53 and 54 operate the valve 28 so that the exhaust ports are brought into substantially vertical alinement with the exhaust ports in the cylinder head so that on the beginning of the exhaust stroke of the piston the said ports begin to open the exhaust passages in the cylinder head. At the point of opening of the said exhaust ports, the crank of the secondary shaft 53 is in substantially right angular relation with the connecting rod connecting the rocker arm 39 for reciprocating said valve, consequently the valve moves downwardly very quickly, opening the exhaust ports very rapidly and giving a wide open port with a very short movement of the crank shaft. The crank of the shaft 53 having passed the right angular position in relation to the connecting rod on the opening of the exhaust port, the vertical movement of the said connecting rod is retarded as the said crank approaches the dead center; thus maintaining a wide open port for the maximum period. The secondary shaft 54 during this period moves over the dead center with its connecting rod and as the piston operating within the cylinder approaches the limit of its exhaust stroke the crank of said shaft 54 moves into substantially right angular relation with its connecting rod and operates the rocker arm 60 and connecting rod 50 rotating the valve and closing the exhaust ports very quickly at the completion of the said exhaust stroke. It will thus be seen that a rotary and reciprocatory motion is imparted to the valve 28 65 through the connections with the second-

ary shafts 53 and 54 in such a manner that the ports are both opened and closed with a very quick movement and that a period of comparative rest occurs when the ports are wide open through the change in the relation of the operating cranks and their connecting rods as they approach or pass over the dead centers.

It will be noted from the foregoing description and an inspection of Figs. 5 to 8 inclusive of the drawing that the ports in the sleeve valve approach the corresponding fixed ports in the cylinder in one direction and leave said fixed ports in a direction more or less at right angles to the first direction, the opening and closing movements being rapid and the intermediate movement relatively slow, thus producing the desired quick opening and closing of the ports while obtaining a maximum port area and affording ample opportunity for the inlet and escape of gases. To attain the maximum result from the quick opening and closing movements the edges of the ports which coincide in opening are parallel so that the port is opened throughout its width and the adjacent edges of the ports which coincide in closing are also parallel.

A distinguishing feature of the form of the invention illustrated in the drawings is that the movable ports describe a quarter circle, more or less, in passing the fixed ports and that the edges of each pair of ports which coincide in the opening movement are adjacent to the edges which coincide in the closing movement, whereas in most slide valve movements the movable ports move directly across, or from one side to the opposite side of the fixed ports.

The packing rings are arranged both above and below the row of ports and as the valve 28 is raised so that the ports therein are moved upwardly clear of the ports in the cylinder head, the said packing rings insure the proper closing of the ports during the compression and expansion strokes of the piston.

The valve 28 operates freely in the annular recess formed to the outside of the cap 16 and is thoroughly protected from undue heating by the water jacket 4 arranged between the valve and the combustion chamber, the said water jacket may be extended upwardly between the valve and the exhaust passage, if so desired.

In order to obviate any possibility of undue compression occurring in the chamber in which the valve is inclosed, suitable grooves may be formed in the casing inclosing said valve to allow the free escape of air on the downward movement of said valve.

A very good feature in the construction herein shown and described is that the valve 28 is completely separated from the combustion chamber, being held within a recess

in the casing, consequently it is absolutely free of end pressure from the expansion of the gases.

The spider formation of the upper portion of the valve 28 allows a perfect lubrication, as oil may be fed to fall on the top of the cap 16 and find its way into the valve seat.

The arms of the spider may be slightly concaved so that a certain amount of the oil within the casing would be conducted to lubricate the outer face of the said valve. The construction of the connecting rod 50 and its co-acting parts is important to this device, in order to impart the rotary movement to the said valve, that is to say, the said connecting rod must be swivelly connected at both ends.

In the construction herein shown and described, two separate rows of ports are shown but the arrangement of the ports may be varied if desired as also may the construction and arrangement of the valve.

Various changes in constructional features may be made without departing from the spirit of this invention so long as the essential feature of operating a cylindrical valve with a combined reciprocal and lateral movement resulting in the valve traveling on the surface of the cylinder with a circular movement longitudinally of said cylinder is adhered to, that is to say, so that the port in said valve travels in a substantially circular path, the axis of which is perpendicular to the axis of the cylinder.

What I claim as my invention is:—

1. In an internal combustion engine, a cylinder having inlet and exhaust ports, a piston operating in said cylinder, and a cylindrical valve separate from the piston and having suitable ports, said valve being operated with a combined reciprocal and lateral movement causing the valve ports to travel in a substantially circular path on the surface of the cylinder.

2. In a four cycle internal combustion engine, a cylinder having inlet and exhaust ports, a piston operating in said cylinder, and a cylindrical valve arranged substantially co-axial with said piston and separate therefrom and operated with a combined reciprocal and partial rotary movement causing the valve port to travel in a substantially circular path one diameter of which is parallel with the axis of the cylinder.

3. In a four cycle internal combustion engine, a cylinder having inlet and exhaust ports, a piston operating in said cylinder, a cylindrical valve having ports to co-operate with the cylinder ports, and means for moving said valve so that the port thereof travels in a substantially circular path one diameter of which extends longitudinally of the cylinder.

4. In an internal combustion engine, a cylinder having inlet and exhaust ports, a piston operating in said cylinder, a cylindrical valve separate from the piston, and means operatively connected with said piston for imparting to said valve a substantially circular movement one diameter of which extends longitudinally of the cylinder to control the inlet and exhaust. 70

5. In an internal combustion engine, a cylinder having inlet ports and exhaust ports circumferentially arranged and at right angles to the axis of the cylinder, a piston operating in said cylinder, a cylindrical valve having ports adapted to register with the said cylinder ports, and means for operating said valve to move the valve ports laterally into and out of longitudinal alinement with the cylinder ports and longitudinally to move said valve ports into and out of lateral alinement with said cylinder ports, to open and close the inlet, to retain the gases during compression and firing and to open and close the exhaust. 80

6. In a four cycle internal combustion engine, a main cylinder, a single valving cylinder located in contact with said main cylinder and adapted for performing its valving functions by a combined motion, a piston working within said cylinder but moving independently of the valving cylinder, and an actuating means for imparting motion to the valving cylinder laterally and longitudinally. 90

7. In an internal combustion engine, a four cycle engine valve system, comprising, a main cylinder having inlet and outlet ports at right angles to the axis of the cylinder and near its head, a separately movable cylinder having ports that co-act with the main cylinder ports, a piston moving within said main cylinder, means for oscillating said valving cylinder with less than semi-rotation to carry the ports into and out of longitudinal alinement, and means for reciprocating said valving cylinder with a stroke less than the stroke of the piston to carry said ports into and out of lateral alinement for controlling the admission, compression, retention during explosion, and final expulsion of the working medium. 105 110

8. In an internal combustion engine, a cylinder having suitable inlet and exhaust openings, a cylindrical valve, a main shaft and a valve gear operatively connected to said main shaft and having a rocker arm operatively connected with said valve and adapted to reciprocate said valve, and means operatively connected with said main shaft and with said valve for rotating said valve coincidently with the reciprocal movement. 120 125

9. In an internal combustion engine, a cylinder having suitable inlet and exhaust openings, a cylindrical valve, a main shaft, a secondary shaft operated from said main 130

shaft, and a valve gear having a rocker arm and a link connected to said valve and rotating the same, and means operatively connected to the main shaft for reciprocating said valve.

- 5 10. In an internal combustion engine, a cylinder having suitable inlet and exhaust openings, a cylindrical valve, a main shaft, a plurality of secondary crank shafts operated from said main shaft, and a valve gear having a rocker arm connected to one of said crank shafts and to said valve and reciprocating the same and a rocker arm connected to the other of said secondary shafts and by a link to said valve and rotating the same.
- 10 15. 11. In an internal combustion engine, a cylinder having suitable inlet and exhaust openings, a cylindrical valve, a main shaft, a secondary shaft operated from said main shaft, and a valve gear having a rocker arm operated from said secondary shaft, said rocker arm being operatively connected to said valve and reciprocating said valve and means for rotating said valve.

- 20 25. 12. In an internal combustion engine, a cylinder having inlet and exhaust openings, a cylindrical valve having a spider at the top thereof supporting a central stem, a collar encircling said stem, means for holding said collar on said stem, a main shaft, a secondary shaft, and a valve gear having a rocker arm connected to said collar and to said secondary shaft and means for rotating said valve.

- 30 35. 13. In an internal combustion engine, a cylinder having inlet and exhaust openings, a cylindrical valve having a spider at the top thereof supporting a central stem, a collar encircling said stem, means for holding said collar on said stem, a main shaft, a secondary shaft, and a valve gear having a rocker arm connected to said collar and a rod pivotally secured to its other end, said rod being connected to said secondary shaft and means for rotating said valve.

- 40 45. 14. In an internal combustion engine, a cylinder having inlet and exhaust openings, a cylindrical valve having a spider supporting a central stem and a stud projecting from said spider to one side of the center, a main shaft, a secondary shaft, and a valve gear having a rocker arm and a link pivotally connecting said stud to said rocker arm, and means connected to said stem for reciprocating said valve.

- 50 55. 15. In an internal combustion engine, a cylinder having inlet and exhaust openings, a cylindrical valve having a spider supporting a central stem and a stud projecting from said spider to one side of the center, a main shaft, a secondary shaft, and a valve gear having a rock shaft suitably journaled and operatively connected to said secondary shaft, an arm on said rock shaft, a link con-

nected to said stud and to said arm, and means for reciprocating said valve.

16. In an internal combustion engine, a cylinder having suitable inlet and exhaust openings, a cylindrical valve having inlet and exhaust openings adapted to register with the inlet and exhaust openings respectively in said cylinder, a valve gear having a rocker arm connected to said valve and adapted to impart a reciprocatory motion thereto and a rocker arm connected to said valve and adapted to impart a rotary motion thereto, a main shaft, a secondary crank shaft operated from said main shaft and operatively connected with said rocker arm to reciprocate said valve and a secondary crank shaft operated from said main shaft and operatively connected with said valve to rotate said valve.

20 25. 17. In an internal combustion engine, a cylinder having an enlarged end and inlet and exhaust openings therein, a cap secured within the enlarged upper end of said cylinder and closing in the combustion chamber and forming an annular valve chamber outside of said combustion chamber, said cap having inlet and exhaust openings therethrough registering with the inlet and exhaust openings in said cylinder, a cylindrical valve operating in said valve chamber and having inlet and exhaust ports adapted to register with the ports in said cylinder and cap, a main shaft and a valve gear operated from said main shaft and operatively connected with said valve.

30 35. 18. In an internal combustion engine, a cylinder having a circumferential row of inlet ports and a circumferential row of exhaust ports and inlet and exhaust passages communicating with said ports, said inlet ports being arranged in vertical alignment with said exhaust ports, a cylindrical valve having a circumferential row of inlet ports adapted to register with the inlet ports in said cylinder and a circumferential row of exhaust ports adapted to register with the exhaust ports in said cylinder, the inlet ports in said valve being staggered in relation to the exhaust ports therein, a main shaft, and a valve gear adapted to impart to said valve rotatory and reciprocatory motions.

40 45. 19. In an internal combustion engine, the combination with a cylinder, containing a port, of a piston in said cylinder, a valve containing a port movable on said cylinder and relatively to said piston, and means to move said valve parallel to the axis of the cylinder and at right angles thereto to cause the ports to register at the proper times in the engine cycle.

50 55. 20. In an internal combustion engine, the combination with a cylinder containing a port, of a piston in said cylinder, a valve containing a port concentric with said pis-

ton and cylinder and movable relatively to said piston and means to reciprocate and oscillate said valve to cause the ports to register at the proper times in the engine 5 cycle.

21. In an internal combustion engine, the combination of a main cylinder provided with intake and exhaust ports, a single valving-element consisting of an independently 10 slidable, concentric member with ports located to coöperate with the ports in the main cylinder, said valving element having a movement of reciprocation and oscillation combined that will consecutively open the 15 exhaust and intake passages and close the same during compression and working strokes, an operating piston working within, but unattached to said valving-element, an engine shaft operated by said piston, and 20 means actuated therefrom for controlling the independent movement of said valving element.

22. The combination with a cylinder of an internal combustion engine having inlet and 25 exhaust ports, of a sleeve outside said cylinder in axial coincidence therewith and having ports adapted to register with said ports of the cylinder, and means for imparting to 30 said sleeve a combined reciprocatory and rotary motion to control the inlet to and exhaust from said cylinder.

23. In a four cycle internal combustion engine a fixed cylinder, a cylindrical slide valve rigid against internal pressure co- 35 axial with and outside the cylinder, inlet and outlet ports both controlled by the slide valve, a piston in the fixed cylinder, and means whereby the valve is moved to close the cylinder ports during the compression 40 and explosion cycles of the engine.

24. In an internal combustion engine, a fixed cylinder, a cylindrical slide valve rigid against internal pressure, co-axial with and outside the cylinder, inlet and outlet ports 45 both controlled by the slide valve, means for cooling the fixed cylinder within the cylindrical valve, a piston in the fixed cylinder, and means whereby the valve is moved to close the cylinder ports during the compression 50 and explosion cycles of the engine.

25. In a four cycle internal combustion engine, the combination with a fixed cylinder having inlet and exhaust ports, of a cylindrical slide valve rigid against internal 55 pressure and co-axial with and outside the cylinder and having inlet and exhaust ports

therein, a piston operating in said fixed cylinder, and means whereby the valve is moved to open and close the exhaust and inlet ports successively and to maintain said ports 60 closed during the compression and explosion cycles of the engine.

26. In a four cycle internal combustion engine, the combination with a fixed cylinder having inlet and exhaust ports, of a cylindrical slide valve rigid against internal pressure and co-axial with and outside the cylinder and having inlet and exhaust ports therein, means for cooling said cylinder arranged within the cylindrical valve, a piston operating in said cylinder, and means whereby the valve is moved to open and close the exhaust and inlet ports successively and to maintain the said ports closed during the compression and explosion cycles of the 75 engine.

27. In a four-cycle internal combustion engine, a cylinder having inlet and exhaust ports, a piston operating in said cylinder, a cylindrical valve having ports to coöperate 80 with the cylinder ports, and means for moving said valve so that the ports thereof travel in a substantially circular path, one diameter of which extends longitudinally of the cylinder, one side of each valve port 85 coinciding with one side of the corresponding cylinder port in opening the port and the adjacent side of each valve port coinciding with the adjacent side of the corresponding cylinder port in closing, respectively. 90

28. In an internal combustion engine, a cylinder having inlet and exhaust ports, a piston operating in said cylinder, and a cylindrical valve separate from the piston and having suitable ports, said valve being operated with a combined reciprocal and lateral movement causing the valve ports to travel in a substantially circular path on the surface of the cylinder, one of the component movements of the valve being mainly used 100 to bring the ports in the valve into register with the ports in the cylinder and the other component movement being mainly used to move the valve ports out of register with the cylinder ports. 105
